(57) **CLAIM**

The ornamental design for a GPS unit for a portable wireless telephone, as shown.

DESCRIPTION

FIG. 1 is a perspective view of the top, front and left side of a GPS unit for a portable wireless telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

CERTIFICATE OF CORRECTION

PATENT NO. : Des. 478,070 S
DATED : August 5, 2003
INVENTOR(S) : Michio Nagai, Mika Fujii and Sachio Hattori

Page 1 of 1

It is certified that error appears in the above-identified patent and that said Letters Patent is hereby corrected as shown below:

Title page.

Before Item [57], **CLAIM**, insert -- Be it known that we, Michio Nagai, Mika Fujii, and Sachio Hattori, have invented a new, original and ornamental design for a GPS unit for a portable wireless telephone of which the following is a specification, reference being made to the accompanying drawings, forming a part hereof. --

Signed and Sealed this

Twenty-fourth Day of February, 2004

JON W. DUDAS
Acting Director of the United States Patent and Trademark Office
